CONVERSION OF HYDROCARBON OILS

Richard F. Trow, Port Arthur, Tex., assignor to
The Texas Company, New York, N. Y., a corpora-
tion of Delaware

Application May 4, 1933, Serial No. 669,300

6 Claims. (Cl. 196—49)

This invention relates to the pyrolytic conversion of hydrocarbon oils, more particularly petroleum oils, to oils of lower boiling points.

My invention has for an object the provision 5 of a process for converting hydrocarbon oils which is capable of producing a high yield of light distillate of high anti-knock value and a low yield of heavy distillate or fuel oil from a dirty stock, that is to say, a stock which cannot 10 be subjected to a drastic cracking operation producing a high yield of gasoline per pass without excessive coke formation.

My invention has for a further object the provision of a method of stripping a plurality of tars 15 of different characters drawn from pressure reaction vessels, whereby residual fuel oils of desired characteristics may be obtained in an advantageous manner.

My invention has for further objects such additional improvements in operative advantages 20 and results as may hereinafter be found to obtain.

My invention is especially applicable to an operation conducted for the purpose of converting 25 hydrocarbon oils to oils of lower boiling point in which a stock is subjected to cracking conditions of temperature and pressure, as for example, while passing through a heating coil, the cracked products being delivered to one or more enlarged reaction vessels or stills from which vapors and residual oils in liquid form are separately withdrawn, and more especially to operations of the so-called "low-liquid-level" type, in which liquid is withdrawn from the reaction vessel or vessels at a rate sufficient to prevent accumulation 30 of liquid oil within said vessel or vessels.

My invention contemplates delivering a charging stock, such, for example, as a dirty gas oil 40 or a reduced crude resulting from a previous topping operation, preferably after heating the same to a moderate cracking temperature, into a dephlegmating and distilling zone supplied with hot vapors produced elsewhere in the system. In the dephlegmating zone the more volatile constituents of the charging stock are vaporized and the resultant vapors, together with other vapors from the distillation zone, are withdrawn to a fractionating zone where they are fractionated, for example, by indirect contact with a stream of relatively cool charging stock or by refluxing with a suitable oil, to recover therefrom a clean gas oil fraction suitable for drastic cracking, and a light distillate comprising naphtha or gasoline.

My invention further contemplates the crack-

ing of the clean gas-oil fraction in the manner indicated, that is to say at a relatively high temperature of for example from 900° to 1050° F., the cracked products being delivered to one or more enlarged reaction vessels or stills in which a separation of vapors and unvaporized or residual liquid occurs, the latter preferably being withdrawn at a rate sufficient to prevent accumulation of liquid oil in the reaction vessels or stills. The vapors withdrawn from the reaction 10 vessels or stills are passed to the dephlegmating zone where they are brought into contact with fresh charging stock as aforesaid. Unvaporized oil collecting within the dephlegmation zone, comprising residual constituents of the charging 15 stock and constituents condensed out of the vapors entering from the reaction vessels or stills, is delivered to one or more of the reaction vessels or stills, preferably by being commingled with the stream of hot cracked products entering the 20 same from the high temperature cracking coil.

My invention further contemplates withdrawing residual or unvaporized liquid from one or more of the reaction vessels or stills and subjecting it, preferably while in transit through a 25 heating coil, to a moderate cracking temperature of, for example, from 320° to 380° F. for a sufficient time to break or reduce the viscosity of the liquid without causing deposition of coke to an undesirable extent, and discharging the viscosity- 30 broken stream into a tar stripper or auto-distillation zone. Unvaporized liquid withdrawn from one or more of said reaction vessels at a subsequent point with respect to the flow of vapors through the same, may be introduced into the tar 35 stripper without being passed through a heating coil, and preferably with the admixture of relatively cool oil to reduce volatilization thereof and to produce a combined fuel oil residue of desired characteristics.

In the auto-distillation zone, the oil or tar is subjected to a reduced pressure as compared to the pressure obtaining in the reaction vessels and more particularly in the viscosity-breaking furnace coils, and by means of this reduction of 45 pressure lower-boiling constituents of the oil or tar are liberated in vapor form, while heavy residual constituents suitable for use as fuel oil remain unvaporized and are withdrawn.

The liberated vapors are preferably fractionated 50 to recover therefrom low-boiling constituents such as heavy naphtha or light gas oil, and a heavier fraction, for example, a heavy gas oil. The light gas oil fraction may be combined with the clean gas oil from the fractionation zone 55

about to enter the aforesaid high-temperature cracking coil, or may be used as a reflux in the main fractionation zone or the dephlegmation zone, or both.

5 The heavy gas-oil fraction, on the other hand, may be withdrawn from the system or combined with fresh charging stock for delivery to the dephlegmating zone.

10 With regard to the conditions under which the viscosity breaking of the liquid removed from the reaction vessel or vessels is carried out, it may be said that in general the temperature employed will be sufficient to produce a material reduction of the viscosity of the liquid without 15 causing the deposition of coke to a material extent and to effect a limited amount of cracking per pass, for example, from 6% to 8% of gasoline per pass, and at the most not over 12% of gasoline per pass. As has been indicated hereinabove, 20 a suitable temperature is from 820° to 880° F. The effect of this viscosity-breaking treatment is to make it possible ultimately to obtain larger yields of valuable light cracked distillate without subjecting the liquid thus treated to an operation 25 which would result in excessive coke formation.

30 In order that my invention may be clearly set forth and understood, I now describe with reference to the drawing accompanying and forming part of this specification a preferred manner in which my invention may be practiced and embodied. In this drawing,

35 The single figure is a more or less diagrammatic elevational view of apparatus for accomplishing the conversion of hydrocarbon oil to oils of lower boiling point in accordance with my invention.

40 This apparatus includes a furnace 1 having high-temperature heating coils 2 and an economizer or relatively low-temperature heating coil 3, and also a separately fired furnace 4 having a heating or soaking coil 5.

45 In the present instance, there are provided three enlarged reaction vessels or stills 6, 7 and 8 adapted to receive products from the coils 2, but it will be readily understood by those skilled in the art that the number of such vessels or stills may be varied in accordance with the requirements of individual instances. The dephlegmating zone referred to hereinabove is located within 50 a suitable vessel 10 which may be similar to the reaction vessels or stills 6, 7 and 8 but is preferably provided with internally disposed baffles 11, and the dephlegmation and fractionation of the vapors removed from the vessels 10 is carried out 55 in a fractionating tower 12 of suitable design and preferably provided with a plurality of internally disposed plates or trays 13. Many suitable forms of plates and trays are known in the art and 60 no particular type need be described here in detail.

65 Further dephlegmation of vapors not condensed in the fractionating tower 12 may be accomplished in a dephlegmator 14 provided with a heat-exchange coil 15, while vapors leaving the dephlegmator 14 may be cooled in a condenser 16, the condensed products passing to a gas separator 17.

70 The apparatus, as shown, additionally comprises a tar stripper or auto-distillation vessel 21 which is divided by means of a trap-out tray 21 into a flashing or evaporating section 22, preferably provided with internally-disposed baffles 23, and a dephlegmating or fractionating section 24 which may be provided as shown with

75 suitable internally-disposed plates or trays 25. Uncondensed vapors from the fractionating section 24 of the tar stripper 20 pass to a cooling coil or condenser 26, the resultant products being passed to a gas separator 27. As shown, the apparatus 80 additionally comprises cooling coils 28, 29 and 30, fuel inlets 31 and 32 in the furnace 1 and 4, respectively, and various conduits, pipes or transfer lines, valves and pumps which will be referred to more specifically hereinbelow. 10

85 In practicing my invention, a charging stock, for example, a dirty gas oil, a reduced crude or a mixture thereof, is withdrawn from a source (not shown) through a conduit 35 by means of a pump 36 and may initially be passed through the heat-exchange coil 15 where, by indirect contact with hot vapors passing through the dephlegmator 14, the charging stock may be heated to a temperature of, for example, from 400° to 450° F. It will, however, be understood that if the 90 charging stock is already in a heated condition, it need not be passed through the heat-exchange coil 15, in which event, it is desirable to supply a suitable reflux oil to the dephlegmator 14, or to the fractionation tower 12 to replace 95 reflux which would otherwise be produced by indirect contact of the vapors entering the dephlegmator 14 with the relatively cool charging stock passing through the heat-exchange coil 15.

100 The heated charging stock then passes under a suitable pressure through a conduit 31 to the coil 3 within the furnace 1, where it is raised to a moderate cracking temperature, for example, a temperature of from 750° to 825° F. and preferably about 780° F. The heated charging stock 35 flows from the coil 3 through a conduit 40 having valved branch conduits 41 and 42 leading preferably to the central and lower portions, respectively, of the dephlegmator 10. By regulation of the control valves located within the conduits 41 and 42 it will be apparent that the stream of oil thus delivered to the vessel 10 may be suitably proportioned between the conduits 41 and 42, or may be entirely delivered through either of said 110 conduits.

115 Within the dephlegmator 10 the charging stock is subjected to direct contact with hot products from the still 8 entering the lower portion of the vessel 10 through a conduit 43 and a combined volatilizing and dephlegmating effect occurs, resulting in the vaporization of the more volatile constituents of the heated charging stock as well as condensation of the heavier constituents of the vapors from the still 8. This dephlegmating and fractionating effect may be promoted by means of 120 a relatively cool reflux oil introduced to the upper part of the dephlegmator 10 through a conduit 44.

125 The vapors reaching the top of the dephlegmator 10 pass through a vapor line 45 through the lower part of the fractionating tower 12 and pass upward through the latter. During the upward passage of the vapors through the fractionating tower 12, the vapors are fractionated to produce 130 a clean liquid fraction suitable for high-temperature cracking, such as a gas oil or the like. This fraction collects in the lower portion of the fractionating tower 12 and is withdrawn through a conduit 46. The fractionation is promoted by 135 means of reflux oil supplied to the tower 12 through a line 48, which may serve, as shown, to return to the tower 12 constituents condensed by contact of the vapors with the heat-exchange coil 15 in the dephlegmator 14. Alternatively, however, the 140

reflux supplied to the tower 12 may comprise suitable oil from some other source.

The uncondensed vapors reaching the top of the fractionating tower 12 pass to the dephlegmator 14 through a vapor pipe 47 and from the dephlegmator 14 through a vapor pipe 49 to the condenser 16. The resultant mixture of condensate and gas passes from the condenser 16 through a line 51 having a valve 52 to the gas separator 47, from which gas and naphtha or light cracked gasoline distillate may be withdrawn through valved conduits 53 and 54, respectively.

A portion of the gas oil collecting in the bottom 15 of the fractionating tower 12 may be withdrawn from the conduit 46 through a branch conduit 55 having a valve 56, and may be delivered by pump 57 to a cooling coil 30, from which it passes by way of the conduit 44 into the upper part of 20 the dephlegmator 10 to serve as reflux therein.

The remaining portion or all of the gas oil collecting in the bottom of the fractionating tower 12 passes through a conduit 60 having a valve 61 and a pump 62 to a conduit 63, through which the 25 gas oil is delivered under suitable pressure of, for example, from 200 to 600 pounds per square inch or higher, to the high-temperature coils 2 located in the furnace 1. During its passage to the coils 2, this oil is brought to a relatively high cracking 30 temperature of, for example, from 900° to 1050° F., as aforesaid, and the cracked products then pass through a transfer line 64, having a valve 64' for effecting reduction of pressure when desired, to the upper portion of the enlarged reaction 35 vessel 6.

Within the reaction vessel 6, a separation of the vapors and liquid constituents occurs, the vapors passing through a conduit 65 to the lower portion of the next reaction vessel 7 while residual 40 liquid is withdrawn from the bottom of the reaction vessel 7 through a conduit 66 having a valve 67. In the reaction vessel 7, further digestion and separation occur, the vapors passing through a vapor line 68 to the next reaction vessel 8, while the separated liquid is withdrawn 45 from the bottom of the reaction vessel 7 through a conduit 69 having a valve 70.

Further separation occurs in the reaction vessel 8, the separated liquid being withdrawn from the 50 bottom of the same through a conduit 71 having a valve 72. The valves 67, 70 and 72 are preferably so controlled to maintain the liquid levels within the respective reaction vessels 6, 7 and 8 at a point as low as possible while still permitting 55 operation of the usual float mechanism device (not shown). The vapors then pass from the reaction vessel 8 into the lower part of the dephlegmator 10. Liquid collecting in the bottom of the latter, comprising residual unvolatilized portions of the 60 charging stock combined with condensed constituents of the vapors entering from the reaction vessel 8, as well as residual constituents of any reflux introduced through the conduit 44, is withdrawn from the bottom of the dephlegmator 10 65 through a conduit 73 having a valve 73' and may be delivered by means of a pump 74 and a conduit 75 to the transfer line 63 where it is commingled with the stream of cracked products passing to the first reaction vessel 6.

As an alternative mode of procedure the liquid withdrawn from the bottom of the dephlegmator 10 may be delivered directly to the reaction vessel 6 but it is ordinarily preferable to introduce it to 70 the transfer line 64 as described.

According to the preferred form of my invention, the liquid or tar withdrawn from the reaction vessel 6 through the conduit 66 is delivered under the influence of the pressure obtaining in the vessel 6 to the coil 5 located within the furnace 4, where it is subjected to a moderate cracking temperature of, for example, from 820° to 880° F. and preferably above 860° F. It is preferred to maintain the oil passing through the coil 5 under an elevated pressure of for example about 200 10 pounds per square inch. Where the pressure within the vessel 6 is insufficient to accomplish this, a pump (not shown) may be provided in the conduit 66.

The viscosity-broken stream leaving the coil 5 15 then passes through a conduit 76 having a pressure-reducing valve 77 into the evaporating section 22 of the tar stripper 20, where flashing or auto-distillation takes place resulting in the vaporization of the lower-boiling constituents of the 20 liquid thus introduced.

The relatively refractory liquid withdrawn from the reaction vessel 7 through the conduit 69 may be passed through a conduit 78 having a valve 79 and combined with that withdrawn 25 from the vessel 6 for delivery to the coil 5. Preferably, however, oil or tar withdrawn from the vessel 7 is combined with still more refractory tar from the reaction vessel 8 by passing it through a conduit 80 having a valve 81 and communicating 30 with the conduit 71, through which the combined tar is delivered to the tar stripper 20.

In order to depress volatilization of the more refractory gas oil constituents from the tar delivered to the tar stripper 20 from the reaction 35 vessel 8 or from the reaction vessels 7 and 8, such tar may be cooled in any suitable manner, as for example by means of relatively cool fuel oil introduced to the conduit 71 through a line 82 which preferably communicates with the conduit 40 71 between a pressure-reducing valve 83 located therein and the tar stripper 20.

This feature of my invention is of considerable value and importance irrespective of other features of my invention, and may be applied to 45 the stripping of tars of varying character for the purpose of producing therefrom a fuel oil residue of desired character, in which a final product of desired viscosity or pour test is obtained by inclusion therein of relatively refractory oil, while 50 permitting the volatilization and separation of gas oil or the like which is less refractory and more suitable for further cracking. Where desired, the tar withdrawn from the reaction vessel 6 or from the reaction vessels 6 and 7, as the case 55 may be, may be delivered directly, without cracking or further heating, to the tar stripper 20.

Residual fuel oil is withdrawn from the bottom of the section 22 through a conduit 84 having a valve 84' and leading to the cooling coil 29 from 60 which the cooled fuel oil may be delivered to storage. A portion of this cooled fuel oil may be returned to the conduit 71 for cooling purposes through the conduit 82, wherein are located a 65 pump 85 and a valve 82'.

The vapors pass from the evaporating section 22 into the fractionating section 24 through a vapor line 86. Within the section 24, fractionation of the vapors occurs under the influence of reflux oil introduced to the upper portion of the 70 section 24 through a conduit 87, and heavier constituents of the vapors, which ordinarily comprise a heavy gas-oil fraction, collect in the trap-out tray 21 from which they are withdrawn through a conduit 88 having a valved branch 75

duit 89 leading through the cooling coil 28 to storage. By means of a branch conduit 90 having a valve 91 and a pump 92 part or all of this heavy gas-oil fraction may be delivered to the conduit 37 for delivery to the coils 3 and admission to the dephlegmator 10.

Uncondensed vapors reaching the top of the fractionating section 24 pass through a vapor pipe 94 to the condenser 26 and the resultant mixture of condensate and gas passes to the separator 27 from which gas and condensate, which may comprise a light gas-oil or a heavy naphtha, are withdrawn through valved conduits 96 and 97, respectively. A portion of the condensate withdrawn through the conduit 97 may be diverted through a branch conduit 98 having a valve 99 and a pump 100, by means of which it is delivered through the conduit 87 to the fractionating section 24 of the tar stripper 20 to serve as reflux therein. The remaining portion of the condensate, or if other cooling means are provided for the fractionating section 24 of the tar stripper 20, all of the condensate, may be delivered through a conduit 101 having a valve 102 and a pump 103 and through a branch conduit 104 having a valve 105 to the conduit 63, where it is commingled with gas-oil cycle stock withdrawn from the bottom of the fractionating tower 12 for delivery to the coils 2.

Alternatively, this condensate may be delivered as reflux to the fractionating tower 12, through a branch conduit 106 having a valve 107, or to the dephlegmator 10 through a suitable connection (not shown).

The pressures maintained throughout the system may vary considerably but in general, as has been stated hereinabove, the pressures in the coils 2, 3 and 5 are maintained within a suitable range of, for example, from 200 to 600 pounds per square inch. While similar pressures may be maintained in other portions of the system, it is ordinarily preferred to maintain somewhat lower pressures of, for example, from 150 to 350 pounds per square inch, in the reaction vessels 6, 7 and 8, the distillation vessel 10 and the fractionating tower 12. The pressures within the tar stripper 20 are preferably much lower, for example, from atmospheric pressure or below to 50 pounds per square inch. By means of a pressure-reducing valve 108 located in the line 43, pressures of 150 pounds per square inch, or even less, may be carried in the dephlegmator 10 and fractionating tower 12, where so desired.

It will be obvious to those skilled in the art, therefore, that my invention is not limited to the specific details of the illustrative example or examples set forth and described hereinabove, but may variously be practiced and embodied within the scope of the claims hereinafter made.

90 I claim

1. The process which comprises subjecting a hydrocarbon oil to cracking in a series of cracking stages under superatmospheric pressure, withdrawing residual liquid from an earlier stage and subjecting it to distillation in a zone of reduced pressure, withdrawing a second residual liquid in a more advanced state of cracking from a later stage, cooling said second liquid and introducing it into said reduced pressure distillation zone, and withdrawing a final combined residual liquid from said reduced pressure distillation zone.

2. The process which comprises subjecting a hydrocarbon oil to cracking in a series of cracking stages under superatmospheric pressure,

withdrawing residual liquid from an earlier stage and subjecting it to distillation in a zone of reduced pressure, withdrawing a second residual liquid in a more advanced state of cracking from a later stage, cooling said second liquid and introducing it into said reduced pressure distillation zone, withdrawing a final combined residual liquid from said reduced pressure distillation zone and regulating the degree of cooling of said second residual liquid to produce a final combined residual liquid of a predetermined fluidity. 5

3. The process which comprises subjecting a hydrocarbon oil to cracking in a series of cracking stages under superatmospheric pressure, withdrawing residual liquid from an earlier stage, 10 subjecting it to a moderate cracking temperature and flashing the resultant products in a zone of lower pressure, withdrawing a second stream of residual liquid in a more advanced state of cracking from a later stage, cooling said 20 second stream and introducing it into said low-pressure zone, and separately withdrawing vapors and a final residual liquid from said low-pressure zone.

4. In a process of cracking hydrocarbon oil, 25 wherein said oil is progressed through a series of cracking stages, the steps which comprise withdrawing residual products of cracking from an earlier stage and flashing the same in a zone of lower pressure to liberate lower-boiling constituents in vapor form, withdrawing residual products of further cracking from a later stage, cooling the residual products withdrawn from said later stage, directing the cooled products into said zone of lower pressure, and separately 30 withdrawing liberated vapors and a combined final residuum from said zone of lower pressure.

5. The process of converting hydrocarbon oil into oils of lower boiling points, which comprises subjecting said oil in a distillation stage to direct 40 contact with hot vapors produced in the system, thereby vaporizing lighter constituents of said oil, fractionating vapors from said distillation stage to recover therefrom a light distillate and a heavier recycle stock fraction, subjecting said 45 recycle stock to a relatively high cracking temperature while in transit through a heating coil, discharging the cracked products into a plurality of reaction stages arranged in series, passing vapors from the last of said stages in the series 50 into said distillation stage, withdrawing residual liquid from an earlier reaction stage and flashing it in a zone of lower pressure to liberate lower-boiling constituents in vapor form, withdrawing residual liquid in a more advanced state 55 of cracking from a later reaction stage, cooling it and flashing it into said zone of lower pressure, and separately withdrawing vapors and liquid residuum from said zone of lower pressure.

6. The process of converting hydrocarbon oil 60 into oils of lower boiling points, which comprises subjecting said oil in a distillation stage in direct contact with hot vapors produced in the system, thereby vaporizing lighter constituents of said oil, fractionating vapors from said distillation 65 stage to recover therefrom a light distillate and a heavier recycle stock fraction, subjecting said recycle stock to a relatively high cracking temperature while in transit through a heating coil, discharging the cracked products into a plurality 70 of reaction stages arranged in series, passing vapors from the last of said stages in the series into said distillation stage, withdrawing residual liquid from an earlier reaction stage and flashing it into a zone of lower pressure to liberate 75

- lower-boiling constituents in vapor form, withdrawing residual liquid in a more advanced state of cracking from a later reaction stage, cooling it and flashing it in said zone of lower pressure, and separately withdrawing vapors and liquid residuum from said zone of lower pressure, fractionating said vapors to recover a heavy condensate

therefrom, directing said condensate with liquid withdrawn from said distillation zone, into contact with hot cracked products passing from said high temperature heating coil to said reaction stages.

RICHARD F. TROW.
